PANELING STRUCTURE

Nicholas A. Del Tufo, Bloomfield, N. J.

Application November 8, 1944, Serial No. 562,533

5 Claims. (Cl. 189—88)

This invention relates generally to paneling structure, and particularly to such structure wherein panels of tray shape are secured by clips to a wall or similar surface.

The use of clips for the use of retaining decorative or protecting panels on surfaces such as store fronts is well known in the art. Some of these are of the spring clip type while others serve principally as hooks on which the panels are hung.

The present invention has as a principal object the provision of means of simple structure for positively securing such structural panels in position on a wall or like surface against forces which may tend to dislodge them outwardly from the wall.

Another object of the invention is the provision of a clip device which is adapted to be locked by a simple mechanical act effective through the spaces between panels.

A further object of the invention is the provision in a device of this character of a two-part clip, one part of which is movable into locking engagement with one or more panels after the latter are hung in position on the surface to be covered.

Numerous other objects and advantages of the invention will be apparent as it is explained below with reference to the accompanying drawings which disclose preferred embodiments thereof.

In the drawings:

Fig. 1 shows a clip of a preferred structure in locked engagement with the corner portions of four panels;

Fig. 2 is a sectional view of the device taken along the line 2—2 in Fig. 1;

Figs. 3 and 4 show the two parts of the clip illustrated in Figs. 1 and 2 in exploded view relation;

Fig. 5 illustrates a modified form of the invention;

Fig. 6 is a sectional view taken along the line 6—6 in Fig. 5;

Figs. 7 and 8 show the two parts of the modified form of clip in exploded view relation.

The embodiment shown in Figs. 1 through 4 shows a clip assembly 11 which will be referred to hereinafter as the slide-lock clip. It comprises a base, or primary member 12 and a slide, or secondary member 13.

The modified form of clip shown in Figs. 5 through 8 shows a clip assembly 11' which will be referred to hereinafter as the pivot-lock clip.

It comprises a base, or primary member 12' and its pivot, or secondary member 13'.

Thus, similar parts on both clips will be indicated below by similar numerals, distinction between the two forms being made by use of a prime (') in the designations of pivot-lock clip parts.

Each of the panels, or trays 14 is formed with an exterior wall 15 which is usually decorated or enameled. From the edges of this wall short side walls 16 extend rearwardly, terminating in inwardly turned flanges 17 which lie in a plane substantially parallel to that of the exterior wall 15.

Fastening of the trays 14 to wall beams, strips 15 or other supporting structure 18 of the area to be covered may be effected by clips embodying the present invention in the following manner:

Base members 12 (or 12'), with secondary members 13 (or 13') applied in open positions, 20 are secured by screws 19 (or 19') to the structure 18. These members are located on the wall where the corners of trays 14 will come closest to junction in their final positions, as shown in Figs. 1 and 5.

25 The trays are first hung on hook members 20 (or 20') formed integrally with the base walls 21 (or 21'), the tray flanges 17 at the upper end of the trays engaging these hooks. The outer portions of the hooks preferably are provided with 30 inclined surfaces 22 (or 22') which urge the flanges 17 to rest against the edges or walls 23 (or 23') formed integrally with the base members 12 (or 12') and lock members 13 (or 13').

These walls 23, 23' rise at substantially right angles from marginal portions of the clip members, terminating in edges all of which lie in substantially a plane parallel to the base of the members and the surface to which the members are attached.

40 With the trays thus hung on hook members 20 (or 20'), tray flanges 17 at the opposite or lower ends of the trays are then secured in their positions by means of the slide member 13 (or pivot member 13').

45 If the slide-lock clip is used, the slide 13 will first be released by unscrewing slightly the central screw 19 which passes through an elongated slot 24 in the slide. The slide may then be lowered from its elevated or unlocked position to 50 its lower or locked position, as shown in Figs. 1 and 2. It is moved to this position by any suitable instrument that is insertable between the trays, such as a screw driver.

In locked position, hook members 25 engage 55 the lower flanges 17 of the hanging trays. These

hook members may also be provided with slightly inclined faces 26 to urge the lower flange 17 inwardly against the edges of walls 23.

It is to be noted that the member 13 is not only slidable but is also oscillatable relative to the central screw 19 by which it is secured. This freedom of movement permits each of the two hooks 25 to bear with substantially equal pressure on lower flanges 17 of the two trays engaged by these hooks.

If the pivot-lock clip is used, the pivot member 23' is driven to locked position by applying pressure downwardly to a point about midway along the top wall 13' as indicated at 27 in Figs. 5 and 8. The wall is thus bent to the shape shown in Fig. 5, from its originally straight condition shown in Fig. 8. The necessary pressure to effect this deformation may be applied by any suitable instrument such as the screw driver above mentioned.

As the wall 23' is thus deformed, hooks 25' rotate around the screws 19' from straight or unlocked positions inwardly and downwardly to the locked positions shown in Fig. 5 to effect the same or substantially the same result as that obtained by the locking hooks 25 of the slide-lock above described.

It is believed to be obvious that the base and locking members of these clips may be secured separately to the wall when their use in pairs as shown in the drawings is not desired. For instance, base members may be used along the top of the uppermost row of trays, and locking members along the bottom of the lowermost row.

It is also contemplated by the instant invention that the paired clips intermediate the single members may be either of the structure disclosed in the drawings wherein the members are readily severable, or these members may be united as by flexible portions. Each clip thus integrated may be formed from a single blank in various ways which are believed to be obvious from the invention as disclosed to those versed in the art.

It is believed that it should also be obvious that the invention and its attendant advantages will be clearly understood from the foregoing illustration and description and that many other forms and advantages are contemplated as within the spirit and scope of the invention, the forms herein described being merely preferred embodiments thereof.

I claim:

1. In a paneling structure, panels for covering a wall or like surface in slightly spaced apart relation, said panels having inwardly and oppositely disposed flanges, primary and secondary clip members each provided with hook elements and securable to said wall prior to the applica-

tion of said panels and thereafter to hook said panel flanges and positively retain said panels, said secondary clip members being each provided with a pair of said hook elements adjacent opposite extremities, each hook of said pair being adapted to engage the flange of a panel next to that engaged by the other hook, said clip being movable to fixed panel engaging position by means insertable in the spaces between said panels.

2. A paneling structure of the character described in claim 1 wherein the secondary clip members are each provided with centrally disposed means for securing said clips to said wall including an elongated slot in said clip whereby said hook elements are free to oscillate slightly as they are moved into fixed panel engaging position.

3. A paneling structure of the character described in claim 1 wherein the secondary clip members are united to their primary clip members by pivotal connections, one connection adjacent each of the two hook elements of each secondary element, the portion of said secondary member intermediate said hook elements being deformable by pressure applied thereto by said means insertable between the panels, said deformation effecting the turning of said secondary hook elements on said pivotal connections and into fixed panel engaging positions.

4. A clip assembly for securing panels to a wall or like surface comprising a base member and a secondary member, said secondary member being provided with a pair of spaced elements adapted positively to engage portions of said panels, and an elongated slot formed therein between said elements through which a fastening means, such as a screw, is insertable, whereby said member is securable to the wall, said fastening means also serving as a pivot on which said elements are free to oscillate slightly as they are moved into fixed panel engaging position by means insertable between the panels.

5. A clip assembly for securing panels to a wall or like surface comprising a base member and a secondary member, said secondary member being provided with a pair of spaced elements adapted positively to engage portions of said panels, a deformable bridge portion connecting said elements, and a fastening means, such as a screw, insertable through a hole in said member adjacent each of said spaced elements, whereby said member is securable to the wall, said fastening means also serving as pivots on which said elements oscillate into fixed panel engaging positions when said bridge portion is deformed by means insertable between the panels.

NICHOLAS A. DEL TUFO.
